UNITED STATES PATENT OFFICE.

HERBERT M. LOFTON, OF SAVANNAH, GEORGIA.

LOCOMOTIVE-BRAKE.

SPECIFICATION forming part of Letters Patent No. 516,569, dated March 13, 1894.

Application filed April 6, 1893, Serial No. 469,343. (No model.)

To all whom it may concern:

Be it known that I, HERBERT M. LOFTON, a citizen of the United States of America, and a resident of Savannah, in the county of Chat-
ham and State of Georgia, have made certain
new and useful Improvements in Locomotive-Brakes; and I do hereby declare the following to be a full, clear, and exact description
of the invention, such as will enable others
skilled in the art to which it appertains to
make and use the same, reference being had
to the accompanying drawings, and to letters
and figures of reference marked thereon,
which form a part of this specification.

This invention relates as above stated to
air-brakes having particular reference to the
class of such devices as are used on locomotives
and operated from the cab thereof, the
object being to so improve this class of de-
vices, further than the improvement set forth
and covered in and by my former Letters
Patent No. 476,283, dated June 9, 1892, as
to render them still more effective and dura-
ble under the peculiar conditions and strains
to which they are subjected, the details of all
of which will be hereinafter fully specified
and claimed.

In the accompanying drawings, Figure 1 is
a side elevation of the device as constructed
and attached in the case of an ordinary two-
wheeler passenger locomotive. Fig. 2 is a
like view but of a modification of the device
shown in Fig. 1, showing the connection to
the piston when it is impossible for the cyl-
inder to be placed vertically. Fig. 3 is an
elevation of the back side of the brake shoe,
hanger, and connected elements, the upper
end of the hanger being in section to show
its manner of suspension. Fig. 4 is a section
of Fig. 3 on the center of the brake shoe,
showing the hanger and shoe, the pivoting
block on the locomotive truck-frame, the con-
nections being such as are shown in the
modified Fig. 2. Fig. 5 is a side elevation of
the lever for comparison with Fig. 4, said le-
ver being such as is shown in connection with
Fig. 1. Fig. 6 is a detail of the rod connect-
ing the two sections of the brake. Fig. 7, is
a view of the novel form of hanger, and Fig.
8 is a view looking from the right hand side
of Fig. 7. Fig. 9 is a view of the hanger

strengthening brace, and Fig. 10 is an edge
view thereof.

In the figures, like reference characters are
uniformly employed in the designation of 55
corresponding elements of construction.

A designates the truck-frame, B, the wheels
and C the axles, all of which are usually em-
ployed for their several functions, although
their construction is immaterial to the proper 60
working of the device.

The brake shoe 1, which is of the usual
form with the exception that it carries on its
back side two backwardly projecting lugs 2,
having between them a space of the requisite 65
width, is suspended from the frame by the
hanger 3, being pivotally seated on the wrist-
pin 4 thereof. The hanger 3 is pivotally se-
cured to the frame on a pin 5 which is in-
serted in or forms part of a bracket 6 secured 70
to the frame A in the proper position. The
stability of the relative positions of the pin
4 and the hub of the hanger 3 and the pin 5
is insured by the link 7, which is seated on
said pins 4 and 5 extending between them, 75
and also serving as washers under the pins 8
which secure the parts in place. This con-
struction prevents one of the effects of the
torsional strains incident to the required
heavy braking and remedies a fault in the 80
class of brakes as now constructed.

Pivoted on the pin 4 which passes through
the lugs 2 on the brake shoe is a lever 10 as
best shown in Fig. 5, having a short down-
wardly extending arm 11 and a longer in-
wardly extending horizontal arm 12, the for-
mer having a hole (one or more) and the lat-
ter having a longitudinally extending slot 13
in its end. The said arm 11 is connected by
means of a pitman 14 with the brake-shoe on 90
the other hanger, being secured to the pin 9
thereof between the lugs 2, whereby equali-
zation of pressure is had. The arm 12 is se-
cured by a pin passing through the slot there-
of, to the piston-rod of a vertically-arranged 95
pressure cylinder. The vertical movements
of the said piston-rod obviously applies and
releases the brakes by a semi-rotary move-
ment of the lever 10 on its axis, an upward
movement of the arm 12 applying the brakes 100
equally on both wheels and a downward
movement thereof releasing them.

Fig. 2, shows a short upward extension 10' in lieu of the lever 10, a vertical lever 10" pivoted to the frame and extending above and below same, connected at its upper end 5 with a horizontally arranged piston-rod 10", and being at its lower end connected with the lever 10', the construction otherwise being the same as in Fig. 1.

Having thus described my invention, what I claim as new, and desire to secure by Letters Patent, is—

1. In a device of the class specified, a truck having wheels thereon, pendent arms and brake shoes thereon carrying lugs centrally 15 of their back sides, a double lever pivoted between the lugs on one shoe, and connected to the braking power at its upper end, a pitman secured to lower end and pivotally secured between the shoe lugs on the back of

the other shoe, substantially as and for the purpose specified.

2. In a device of the class specified, a truck, wheels thereon in combination with the hanger having a hollow hub seated on a pin secured to the frame and carrying a wrist pin on its lower end, the brake shoe seated revolubly on said pin, a link perforated in its ends, one end engaging the pin on the frame and the other end engaging the wrist pin, and means for applying and releasing the brakes, for the purpose specified.

In testimony whereof I hereunto affix my signature in presence of two witnesses.

HERBERT M. LOFTON.
